ROBERT ALKAN AND GEORGES LESOURD, OF PARIS, FRANCE.

HOOKING RING FOR A MASS SUSPENDED TO RELEASEING DEVICES.

Application filed June 29, 1925. Serial No. 40,364.

To all whom it may concern:

Be it known that we, ROBERT ALKAN and GEORGES LESOURD, citizens of the French Republic, both residing at Paris, France, have 5 invented certain new and useful Improvements in a Hooking Ring for a Mass Suspended to Releasing Devices, of which the following is a specification.

This invention relates to a ring or loop 10 allowing to suspend a mass to a releasing device with automatic hooking and arranged in such a manner as to allow the use of a simple lifting apparatus to secure the hooking or hanging of the mass to the releasing device.

This ring which may be used for instance with projectiles, mail bags and the like thrown from airships is characterized by 20 the presence of three eyes: one for the passage of the suspension hook, one for the attachment of the mass, one for the attachment to the lifting gear, these three eyes being arranged in such a manner that, when the mass is suspended to the lifting gear, 25 the eye for the attachment to the mass takes a position which is vertical in relation to the former one, while the eye of the suspension hook is located at a certain distance from this vertical line in such a position 30 that the mere lifting or hoisting of the mass or body brings the eye adapted to be attached to the suspension hook to such a suitable position relatively to the suspension hook forming part of a releasing device 35 of a known system and of such form that the passage for the hoisting rope is left entirely free.

When the ring is hooked and when it is 40 possible to slacken the lifting cable, the ring is slightly shifted and the point of fastening or attachment to the mass places itself vertically to the contact point between the ring and the hook.

A form of construction of this ring is 45 shown by way of example in the accompanying drawing in which:

Fig. 1 is a perspective view of the ring.

Fig. 2 is a side view thereof partly in section.

50 Fig. 3 shows the ring in the position of rest.

Fig. 4 shows, on a smaller scale, the ring in the hoisting position.

Fig. 5 shows the ring when hooked.

55 In this drawing, 1 is the eye for the hook-

ing of the ring and 2 is the eye which is used for attaching the lifting gear 8, the hoop 8^a of which passes through the slot 5 and is engaged into the shaft 6. This shaft 6 which is put in position for the hoisting 60 operation and which is removed after the mass has been hooked or fastened, is steadied during the hoisting operation through wedging between the faces *a* and *b* on the one hand and the face *c* of the lifting loop on 65 the other hand. This shaft 6 can moreover be stopped through the medium of a shoulder or projection 6^a of the free end or by means of a pin or a safety pin which can be easily taken apart. 3 is the eye 70 adapted to be secured to the mass or body 9 by means of a shaft 4.

In the position of rest, the ring is turned down upon the wall of the mass 9 to be 75 suspended as shown in Fig. 3.

In the hoisting position as shown in Fig. 4, the ring is in balance between two equal and opposite powers: 1st, the weight of the load *P* exerted upon the fastening point *m* of the mass; 2d, the lifting strain *H* exerted 80 upon the fastening point *n* of the cable 8. In this position, the hooking or fastening eye 1 is thrown beyond the vertical of the suspension point and comes into the suitably arranged hook *C* of the releasing device. The upper edge of the ring pushing the upper face of the hook opening causing the revolution and the closure of the throwing in device. 85

The ring is then fastened. When the cable 90 or rope 8 is slackened (Fig. 5), the ring assumes such a position that the point *m* at which this ring is secured to the mass takes under the action of weight a vertical 95 position relatively to the hooking or fastening point *o*.

The loop of cable 8 can then be unhooked and the body or mass 9 remains simply suspended to the hook of the releasing device. 100

According to the above described arrangements, the ring shows the following features:

1. The ring can be turned down over the mass in the position of rest. 105

2. In the hoisting position, the eye securing the attachment or fastening to the suspension hook of the releasing device is removed from the hoisting line.

3. In the position of fastening to the re- 110

leasing device, the eye for attaching the hoisting cable is removed from the vertical of the suspension point.

We claim:—

- 5 A suspension ring for a mass or body adapted to be secured to a releasing device, characterized by the fact that it comprises, in combination, an eye for fastening the mass to be suspended, then, thereabove, an eye for the purpose of fastening to a lifting or hoisting gear, and further above, an eye for the attachment to the releasing gear,

this latter eye being at right angle with the two other eyes and being placed outside the plane passing through the axes of 15 these two other eyes, in order to be thrown in the hoisting position, outside the vertical passing through the two lower eyes for the purpose of allowing the easy hooking or fastening to the suspension hook. 20

In testimony whereof we affix our signatures.

ROBERT ALKAN.
GEORGES LESOURD.
